(57) **CLAIM**

The ornamental design for a holder for dish towel and sponge as shown and described.

DESCRIPTION

FIG. 1 is an elevated perspective view of the holder for dish towel and sponge;

FIG. 2 is a side perspective view thereof;

FIG. 3 is an upper elevated perspective view thereof;

FIG. 4 is a top perspective view thereof;

FIG. 5 is a rear side perspective view thereof;

FIG. 6 is an end perspective view thereof;

FIG. 7 is a side perspective view thereof at an opposite side than shown in FIG. 1;

FIG. 8 is an unclaimed side perspective view thereof including an unclaimed strap for holding the holder for dish towel and sponge in position, the unclaimed strap shown separate from the holder for dish towel and sponge and comprising unclaimed environment;

FIG. 9 is an unclaimed side perspective view thereof including an unclaimed strap for holding the holder for dish towel and sponge in position, the unclaimed strap shown attached to the holder for dish towel and sponge and comprising unclaimed environment; and,

FIG. 10 is an unclaimed top perspective view thereof including an unclaimed strap for holding the holder for dish towel and sponge in position, the unclaimed strap shown attached to the holder for dish towel and sponge and in a closed position and comprising unclaimed environment.

The unclaimed strap shown in a faded appearance in FIGS. 8-10 shows environment that forms no part of the claimed design.
